(57) **CLAIM**

We claim the ornamental design for a knife, as shown and described.

DESCRIPTION

FIG. 1 is a rear perspective view of a knife, showing our new design;

FIG. 2 is a right side view thereof;

FIG. 3 is a left side view thereof;

FIG. 4 is a top view thereof;

FIG. 5 is a bottom view thereof;

FIG. 6 is a front view thereof;

FIG. 7 is a rear view thereof; and,

FIG. 8 is an enlarged perspective view showing the claimed area of FIG. 1.

The dot-dash broken lines represent boundaries of the claimed design and form no part of the claimed design. The broken lines depicting the remainder of the knife show features that form no part of the claimed design.

1 Claim, 5 Drawing Sheets
